UNITED STATES PATENT OFFICE.

WILLIAM D. FORSYTH, OF YOUNGSTOWN, OHIO, ASSIGNOR TO RAILWAY PRODUCTS CORPORATION, OF BUFFALO, NEW YORK, A CORPORATION OF NEW YORK.

PRESSED-STEEL BOLSTER.

1,173,715.

Specification of Letters Patent. Patented Feb. 29, 1916.

Application filed July 26, 1915. Serial No. 41,826.

To all whom it may concern:

Be it known that I, WILLIAM D. FORSYTH, a citizen of the United States, and a resident of the city of Youngstown, in the county of Mahoning and State of Ohio, have invented a new and useful Improvement in Pressed-Steel Bolsters, of which the following is a specification.

This invention relates to bolsters for the 10 trucks of railway cars, and particularly to bolsters which are composed of pressed steel main members which are riveted together and braced at the middle in the form of a truss.

15 The objects of the invention are strength, lightness, low cost and durability of bolsters, and adaptability for use in existing types of car trucks.

The invention consists in making the 20 bolster in two principal load carrying members, one of which is partly a tension member and partly a compression member and the other is a combined compression member and lateral stiffener, and riveting them 25 together to embrace a middle brace or post, and in the bolster thus produced, which acts as a truss for carrying the weight on the center-plate, and which acts as a horizontal girder for withstanding lateral pressure, side thrust and twisting forces.

30 Further objects of the invention appear hereinafter in connection with the description of the preferred form of the invention illustrated in the accompanying drawings; and what the invention consists in is more particularly defined in the appended claims.

In the drawings, wherein the same reference characters designate like parts in the several views, Figure 1 is a top plan view 40 of a bolster embodying the invention; Fig. 2 is a side elevation of the bolster shown in Fig. 1, partly in section on the longitudinal center line; Fig. 3 is a bottom view, and Fig. 4 is an end view, of the same; Fig. 5 is a cross-section of the same on the transverse center-line; Fig. 6 is a top plan view 45 and Fig. 7 is a side elevation of the main tension and compression member; and Figs. 8 and 9 are a top plan view and a side 50 elevation, respectively, of the main compression and stiffener member of the bolster.

The principal members of the bolster are the tension and compression member 11, which forms the chords of a diamond truss, 55 and the combined compression and stiffener

channel 12, these members are substantially co-extensive and are riveted together for their entire length to form a rigid beam. The diamond truss member 11 is made from sheet steel by slitting a suitable blank 60 lengthwise along two lines parallel to its margins nearly from end to end, forming three distinct sections which remain integrally connected at their ends, and by bending down the middle section thereof to form the tension tie 13. The side sections are bent at right angles to the original plane of the sheet, forming two side compression members 14. The brace or center post 15 is inserted between the sides 14 and rests 65 at its lower end on the tie 13. The compression and stiffener channel 12 is made from a suitable blank by bending down the side margins 16 to form a channel which is inverted over the sides 14 and riveted thereto 70 for its entire length by horizontal rivets through the sides 14 of the member 11 and side margins 16 of the member 12.

The ends of the channel 12 are bent down 75 to form pockets for the spring blocks 17. The inner sides of the pockets for the spring blocks are closed by angles 18, which are riveted to the under side of the tie portion 13 of the truss member 11. The top of the center brace or post 15 is provided with a 80 flat plate, which is riveted to the under side of the middle of the channel-shape member 12; and the center pivot-bearing-plate 19 is riveted on top of the channel-shape member 12 at its middle immediately over the 85 center brace. Side bearings 20 of pressed metal are riveted on top of the channel-shape member 12 on each side of the center plate toward the ends of the bolster. On each side of the bolster at its ends are riveted 90 guide plates 21 for the truck bolster guides. The rivets which secure these guide plates are riveted through both the side marginal flanges 16 of the channel 12 and the sides 14 of the diamond truss 11.

100 The invention is not restricted to the precise forms and arrangements of the parts as shown and described.

What I claim as my invention and desire to secure by Letters Patent is:

105 1. A car part having a truss member with side sections forming compression chords and a middle section forming a tension chord integrally connected at their ends, a middle brace positioned between said sides 110

- and bearing on said tension chord, and a top channel-shape member inclosing said sides and being riveted thereto from end to end, said channel member being connected at the 5 middle to said brace.
2. A car part having a truss member with side sections forming compression chords and a middle section forming a tension chord integrally connected at their ends, a 10 middle brace positioned between said sides and bearing on said tension chord, and a top channel-shaped member inclosing said sides and being riveted thereto from end to end, said channel member being connected 15 at the middle to said brace, and the ends of said channel being bent down to inclose the ends of said truss member and form with the sides thereof pockets for bearing blocks at the ends of said truss member.
- 20 3. A car bolster having a truss member with side sections forming compression chords and a middle section forming a tension chord integrally connected at their ends, a middle brace positioned between said 25 sides and bearing on said tension chord, and a top channel-shape member inclosing said sides and being riveted thereto from end to end, said channel member being connected at the middle to said brace, and a center 30 bearing plate and side bearing plates riveted to the top of said channel member.
4. A car part having a truss member with side sections forming compression chords spaced apart farther at the middle than at 35 the ends and a middle section forming a tension chord, said sections being integrally connected at their ends, a middle brace positioned between said sides and bearing on said tension chord and a top channel-shape 40 member widest at the middle and growing narrower toward the ends to conform to the spacing of said side sections, said channel-member inclosing said sides and being riveted thereto from end to end, said channel- 45 member being connected at the middle to said brace.

5. A car part having a truss member, a middle brace and a top channel-shape member riveted to said truss member from end to end, said channel-member being connected 50 at the middle to said brace, and the ends of said channel being bent down to inclose the ends of said truss member.

6. A car part having a truss member, a middle brace and a top channel-shape member riveted to said truss member from end to end, said channel-member being connected 55 at the middle to said brace, and the ends of said channel being bent down to inclose the ends of said truss member, and form end 60 pockets for bearing blocks.

7. A car bolster comprising tension chord, compression chord and middle brace, said tension chord having flanges along its sides at its two ends, the end flanges of each 65 side being integrally connected by a member extending alongside of and forming part of the compression chord and said compression chord having side walls embracing said flanges and connecting members 70 from end to end and which are rigidly secured to said flanges and connecting members throughout their length.

8. A car bolster comprising tension chord, compression chord and middle brace, said 75 tension chord having flanges along its sides at its two ends, the end flanges of each side being integrally connected by a member extending alongside of and forming part of the compression chord and said compression 80 chord having side walls embracing said flanges and connecting members from end to end and which are rigidly secured to said flanges and connecting members throughout their length, and the ends of said compression chord being secured across the ends of said tension chord and turned down to form end pockets beneath the ends of said 85 tension chord.

Signed at Pittsburgh, Pa., this 22nd day 90 of July, 1915.

WILLIAM D. FORSYTH.
